(57) **CLAIM**

I claim the ornamental design for wall hanger for watering hose and hose fittings, as shown and described.

DESCRIPTION

FIG. 1 shows a perspective top view of a wall hanger for watering hose and hose fittings;

FIG. 2 shows a top view of the wall hanger for watering hose and hose fittings of FIG. 1;

FIG. 3 shows a bottom view of the wall hanger for watering hose and hose fittings of FIG. 1;

FIG. 4 shows a frontal view of the wall hanger for watering hose and hose fittings of FIG. 1;

FIG. 5 shows a back of the wall hanger for watering hose and hose fittings of FIG. 1;

FIG. 6 shows a left-hand lateral view of the wall hanger for watering hose and hose fittings of FIG. 1; and,

FIG. 7 shows a right-hand lateral view of the wall hanger for watering hose and hose fittings of FIG. 1.
